UNITED STATES PATENT OFFICE.

WILLIAM H. SCHOFIELD, OF BROOKLYN, NEW YORK, ASSIGNOR TO THE SANITARY HEATING COMPANY, A CORPORATION OF NEW YORK.

GAS-HEATER.

1,378,624

Specification of Letters Patent. Patented May 17, 1921.

Application filed June 16, 1920. Serial No. 389,469.

To all whom it may concern:

Be it known that I, WILLIAM H. SCHOFIELD, a citizen of the United States, residing at Brooklyn, in the county of Kings and State of New York, have invented certain new and useful Improvements in Gas-Heaters, of which the following is a full, clear, and exact description.

This invention relates to gas heaters of 10 that character which are used ordinarily to heat rooms or other spaces either by location in a fire place whence it throws heat forward into the room or by location at any suitable point in the open room or space where it 15 radiates heat and circulates heated air in all directions.

Many of the heaters of this class which have been in use heretofore have proven unsatisfactory by reason of the poor or incomplete combustion of the gas which occurs therein and which results in a pollution of the surrounding atmosphere and excessive expense of fuel. To prevent the emission into the room of carbon monoxid resulting from the incomplete combustion it has sometimes been necessary or desirable to connect the heater with a chimney to carry off the products of the incomplete combustion. The connection to the chimney however also carries off much of the heat and the device for that reason becomes even less economical.

The primary object of my invention is to provide a gas heater in which complete combustion of the fuel will take place and which shall be of a simple and comparatively inexpensive construction. A further object is to provide a gas heater affording large radiating capacity as well as a capacity to rapidly heat the surrounding atmosphere by convection. To accomplish these and other objects I provide a gas heater comprising a combustion chamber, a heating chamber and a heating structure interposed between the two chambers, the heating structure having tortuous passages whose walls are subjected to radiant heat from the flames and through which the products of combustion together with the inflowing air are compelled to pass in close association to complete the combustion that is initiated at the burner. The capacity of the tortuous passages is such as to slow down the movement of air through the heater sufficiently to insure the complete combustion of the fuel in the combustion chamber and passages, the

heated air and harmless products of combustion thence passing into the heating chamber where some of their heat is absorbed by the walls of said chamber, and finally into the surrounding atmosphere to promote the circulation thereof. The invention also includes other minor features which will be included in the more detailed description which follows:

In the accompanying drawings: 65
Figure 1 is a front elevation, one-half in vertical section, of my improved gas heater of the form adapted for location in a fire place.

Fig. 2 is a skeleton section on the line *xx* 70 of Fig. 1.

Fig. 3 is a perspective view of the form of heater adapted for location at any convenient place within the space to be heated.

Fig. 4 is a plan of the diaphragm separating the upper and lower compartments of the heater. 75

Fig. 5 is a section on line *yy* of Fig. 4 and

Fig. 6 is a plan of the diaphragm located 80 below the burner.

The specific features of invention disclosed and claimed herein may be embodied in either of the two types of heater illustrated, the main differences between the two heaters being that in the case of the fire place heater the casing is made to conform somewhat to the shape of the fire place in which it is to set and the ornamentation is confined to the front portion which alone is presented to the room, while in the case of the heater which is adapted to stand in the room like an ordinary stove the casing is of symmetrical formation and more or less ornamented on all sides, its front portion however, as in the case of the fire place 85 heater, being constructed to simulate an open grate fire and with doors affording access to certain portions of the heater.

The casing of both heaters is indicated by 1 and is of a general rectangular shape, the 100 width and the height being approximately equal, while the depth is considerably less. The casing is provided with two compartments or chambers 2 and 3 respectively, the former occupying the lower portion of the 105 casing and the latter the upper portion, the two chambers being separated by a horizontal diaphragm 4. The lower compartment 2 is the combustion chamber in which is located a gas burner 5 consisting of a 110

single straight run of pipe preferably of aluminum, extending laterally along the middle of the chamber, the pipe having a row of burner openings or nipples along the top for the emission of gas. This burner is to be connected with a gas service system by pipe 6 which passes along the front and lower portion of the heater and contains a regulating valve 7 and a supply valve 8 by which the flow of gas to the burner is controlled. It may be mentioned that the valve 7 is fixed in its adjustment to supply a constant quantity of gas regardless of the pressure in the system, while the other valve 8 is used to modify the uniform pressure and supply as desired.

The upper compartment 3 is an open space serving as a heat closet through which the heated air and products of combustion pass to the atmosphere, in the meantime giving up heat to the walls of the closet from which it is radiated into the room. The front wall of this heat closet may be reticulated as indicated at 9 in Fig. 1, and is provided with doors 10 through which access may be had to the closet for the purpose of introducing or removing cooking vessels. The floor of the heat closet, which is the diaphragm 4, is provided at its middle portion immediately back of the front doors, with an opening normally covered by a lid 11, while adjacent the lid and toward each end of the diaphragm it is provided with a grating or series of perforations 12, extending substantially from front to rear of the diaphragm. Immediately beneath the diaphragm there is provided a heating structure 13 formed of sheet or cast metal and either integral with the diaphragm or attached thereto, this heating structure being preferably duplicate, as shown, and arranged to the right and left of the middle portion of the diaphragm where the lid 11 is located. Each of these structures is provided with a passage 14 which opens at one end to the combustion chamber 2 at a point near the middle and upper part thereof, thence runs tortuously back and forth and connects with a set of the openings 12 in the diaphragm to establish communication between the upper and lower chambers. As seen in Fig. 2 the passage vertically is shallow but in width is substantially equal to the depth of the main casing the two structures covering the diaphragm except at its middle. These heating structures are located directly above the burner so that they become highly heated during the operation of the device and are adapted to impart their heat to products of combustion and air which are compelled to flow through the passages in moving from the combustion chamber to the hot closet. The entrance from the combustion chamber to the tortuous passages of the heating structure is placed ad-

acent the upper middle portion of the chamber because the circulating gases in the chamber converge at that region and unless carried away at once would burn and discolor the front wall of the casing. At the same time, the middle part of the diaphragm containing the lid is not shielded from the frame and is therefore heated sufficiently to enable light cooking to be done in a vessel placed upon the lid or over the lid opening. 75

Across the bottom of the combustion chamber 2 is a diaphragm 15 which for the most part is an imperforate plate. Along the middle directly beneath the burner pipe 5 this diaphragm is provided with a screen 86 or a narrow field of perforations 16 which serves to equalize and direct the flow of air from below into the combustion chamber. The perforated area being narrow and directly under the burner tube, compels all of 85 the air that enters from below to pass upward on each side of the rod of flames rising from the burner, thus stiffening the flames and promoting the combustion of the fuel. The air inlet at the base of the heater may 90 have flue openings variously placed in the walls of the heater below the level of the diaphragm 15.

In this heater the fuel is burned without preliminary mixing with air and the flames 95 are therefore luminous, the light and heat therefrom being directed by a reflector 17 through a grated and colored window 18 simulating an open grate fire.

In the operation of the heater all of the 10 air that enters the combustion chamber together with the products of combustion must pass through the tortuous passages of the heating structures 13 and in so going any fuel not fully consumed is brought into contact with the hot walls of the structures 13 while in close association with the air and is fully consumed or converted by the time it passes into the heating chamber or heat closet 3, through the openings 12. The tortuous passages are sufficiently restricted to slightly delay the flow of gas from the lower to the upper chamber to permit of the continued and complete combustion of the fuel. From the hot closet the heated gases pass 11 to the outer atmosphere and a rapid circulation thereof is set up and maintained while the heater is in operation. The heating structure 13 with the tortuous passages not only serves to promote and complete the 12 combustion of the fuel, but also absorbs a large amount of heat radiated from the flames, which together with the heat absorbed by the walls of the heater, converts the structure into an effective heat radiating 125 unit.

I claim:

1. A gas heater comprising a lower combustion chamber containing a gas burner, an upper heating chamber, a perforated dia- 130

phragm separating said chambers and a heating structure provided with a tortuous passage leading from the middle portion of the combustion chamber to the perforations in said diaphragm.

2. A gas heater comprising a lower combustion chamber containing a gas burner, an upper heating chamber, a horizontal perforated diaphragm separating said chambers and a heating structure comprising two separated parts one located under each end of the diaphragm and each part having a passage for products of combustion leading from the space between the parts to perforations in the diaphragm.

3. A gas heater comprising a lower combustion chamber containing a gas burner, an upper heating chamber, a horizontal diaphragm separating the two chambers, said diaphragm having an imperforate middle portion with perforated portions each side thereof, and two heating structures located beneath the diaphragm, said structures each having a tortuous passage leading from a point adjacent to the imperforate middle

portion of the diaphragm to the perforated portions thereof respectively.

4. A gas heater comprising a combustion chamber having an elongated burner in the lower portion thereof and a heating structure above the burner and extending longitudinally thereof, the heating structure having a tortuous passage affording the sole exit for products of combustion from the chamber the entering into said passage being adjacent the middle upper part of the chamber.

5. A gas heater comprising a lower combustion chamber containing a gas burner, an upper heating chamber, a diaphragm separating the chambers and having an opening adjacent its middle portion and a heating structure located beneath the diaphragm and having a passage therein leading from the middle portion of the heater to the side thereof and thence returning and connecting with the said opening in the diaphragm.

In witness whereof I hereunto subscribe my signature.

WILLIAM H. SCHOFIELD.
